UNITED STATES PATENT OFFICE.

LOUIS SIDERMAN, OF DETROIT, MICHIGAN.

NECKTIE-HOLDER.

1,268,396.

Specification of Letters Patent. Patented June 4, 1918.

Application filed November 13, 1917. Serial No. 201,888.

To all whom it may concern:

Be it known that I, LOUIS SIDERMAN, a citizen of the United States of America, residing at Detroit, in the county of Wayne 5 and State of Michigan, have invented certain new and useful Improvements in Necktie-Holders, of which the following is a specification, reference being had therein to the accompanying drawings.

10 This invention relates to a necktie holder, and the primary object of my invention is to provide a simple and durable device that may be advantageously employed for holding a bundle or plurality of neckties or 15 other merchandise, so that the neckties can be easily and safely handled and properly displayed for observation and selection.

Another object of my invention is to provide a necktie holder in which one or more 20 neckties may be held without injury to the same and in such a manner that a selected necktie may be withdrawn, without necessarily interfering with the remaining neckties in the holder.

25 A further object of my invention is to provide an inexpensive and attractive necktie holder to facilitate a salesman in handling and displaying a variety at a time, and at the same time eliminate the 30 nefarious practice of purchasers in surreptitiously obtaining a tie while a salesman is having a purchased necktie wrapped or delivered.

The above and other objects are attained 35 by a mechanical construction that will be hereinafter specifically described and then claimed, and reference will now be had to the drawing, wherein—

Figure 1 is a perspective view of a holder 40 provided with a plurality of neckties;

Fig. 2 is a plan of the holder in an open position;

Fig. 3 is a cross sectional view of the same closed;

45 Fig. 4 is a perspective view of a modified form of retaining member.

A necktie holder in accordance with this invention, may be made of light and durable sheet metal finished to present a neat and 50 attractive appearance, and it is preferable to have the same rust proof so that ties held in the holder will not be stained or injured.

The holder comprises comparatively flat 55 channel members 1 and 2, and these members gradually taper inwardly from the outer

end thereof to the inner end, so that when said members are placed one on the other there is a tapering casing that is rectangular in cross section, and it is in this casing that 60 a plurality of neckties may be frictionally held, so that the casing will form a handle or device by which all the neckties may be readily handled. The casing formed by the members 1 and 2 will contain the neckties 65 in doubled form and yet permit of the ends thereof being spread apart for observation and displaying purposes.

The members 1 and 2 have walls 3 provided with barrels or hinged members 4 and 70 these barrels or hinge members are adapted to longitudinally aline and receive a pivot pin 5, thereby hingedly connecting the members 1 and 2 so that said members may be swung to a closed position to form the 75 casing, as shown in Figs. 1 and 2.

Other longitudinal walls 6 of the members 1 and 2 have barrels 7 and 8 adapted to longitudinally aline similar to the barrels 4. On one of the barrels 8 is a slide sleeve 80 9 having slotted plate 10 in parallelism with one of the walls 6. The slotted plate 10 is held against the wall 6 by a headed pin 11 extending through the slotted plate and fixed in the wall 6, and said slotted plate and 85 its sleeve may be longitudinally shifted relatively to the wall 6 by an outstanding lug or finger piece 12 at one end of the plate 10. The movement of the plate 10 and its sleeve 9 is such that the sleeve 9 may be shifted on 90 to one of the barrels 7 and in this manner the free edges of the members 1 and 2 may be locked together, so as to maintain said members closed and in the casing form.

Connected to the inner side of the member 1 at one end thereof is a resilient retaining member 13, preferably in the form of a bowed longitudinally disposed spring, and this retaining member is adapted to frictionally engage or exert pressure upon a 100 bundle or plurality of ties within the holder, so that the ties cannot accidentally slip from the holder, but may be individually removed. To obviate any danger of this retaining member tearing or injuring a tie, as 105 it is removed, the retaining member may be provided with a pressure plate 14, as shown in Fig. 4, although said plate may not be necessary, particularly when the ties are of such a nature as not to be easily injured.

110 It is thought that the utility of the tie holder will be apparent without further de-

scription, and while in the drawing there is illustrated a preferred embodiment of my invention, it is to be understood that the structural elements are susceptible to such changes in size, shape and manner of assemblage, as fall within the scope of the appended claim.

What I claim is:—

10 A necktie holder comprising tapering channel members having side walls hingedly connected together so that said members may be closed to form a casing rectangular in cross section with the ends thereof open and from which neckties are adapted to project,

a retaining member disposed longitudinally 15 on the inner side of one of said channel members and adapted to bring pressure to bear on neckties in said holder, and means carried by the other side walls of said channel members adapted for holding said members in a closed position. 20

In testimony whereof I affix my signature in the presence of two witnesses.

LOUIS SIDERMAN.
